UNITED STATES PATENT OFFICE.

AXEL AUGUST ASPLUND, OF AUBURN, NEW YORK.

DEVICE FOR OPERATING VALVES.

Application filed September 28, 1921. Serial No. 503,812.

To all whom it may concern:

Be it known that I, AXEL AUGUST ASPLUND, a citizen of the United States, residing at Auburn, in the county of Cayuga and State of New York, have invented certain new and useful Improvements in Devices for Operating Valves; and I do hereby declare the following to be a full, clear, and exact description of the invention, 10 such as will enable others skilled in the art to which it appertains to make and use the same.

This invention relates to improvements in devices for operating valves and more particularly it relates to a device designed to operate the starting air valve of an internal combustion engine to relieve the cylinder pressure.

The object of the invention is to provide 20 a device of the character indicated of a simple mechanical structure which will operate positively and with precision, while at the same time it will provide means to operate to balance the cylinder pressure.

25 The invention consists in the novel construction, arrangement and combination of parts as hereinafter more particularly described and claimed.

One sheet of drawings accompanies this 30 specification, in which like reference characters indicate similar parts throughout.

Fig. 1 is a side elevation view of my improved device, parts being broken away showing the cam lever in its flexed position 35 and the valve held closed by cylinder pressure;

Fig. 2 is a view similar to Fig. 1 showing the cam lever above the operating cams and the valve opened to relieve cylinder pressure;

40 Fig. 3 is an enlarged detail view of the auxiliary cam for operating to open the valve to relieve cylinder pressure.

The present invention involves subject 45 matter previously described in my copending application, Serial Number 359,415, filed February 17, 1920. It is part of a general improvement of the operating mechanism for a Diesel engine having in view the 50 elimination, so far as possible, of manual operations and the provision of mechanism for effecting the various functions of starting, stopping and reversing such an engine both automatically and with precision in 55 their proper sequence and order.

The present invention relates to the means

for controlling the starting air valve in the cylinder.

In accordance with my present invention, the cylinder starting air valve is provided 60 with a valve head 20 and stem 18. Over stem 18 is a housing 17 carrying, spaced above the head of stem 18, a roller 16. Cam lever 1 is mounted so that one end 3 extends between the head of valve stem 18 65 and roller 16, while the other end of said lever is provided with means to engage a cam 9 operated from the engine shaft by any suitable means (not shown). The compressed air for starting the engine is supplied from a suitable reservoir (not shown) 70 through a pipe 23 leading into a manifold pipe 22 which extends throughout the length of the engine and is provided with connections 21 supplying the compressed air to 75 each of the cylinder compressed air valves. The present invention illustrates the invention as applied to a single cylinder, but it will be readily understood that the unit indicated can be multiplied as desired in 80 the case of multiple cylinder engines.

The cam lever 1 is provided upon one side with a slot 2 adapted to receive member 4 which is pivoted against lever 1 adjacent one end as by a screw 10. Member 4 is further provided with a journal hole adapted 85 to receive eccentric 5 fixedly mounted upon a shaft 6. It will be noted that the slot 2 in lever 1 is made wider than member 4 and member 4 is normally placed against the 90 upper face of slot 2 by means of spring 13 which is compressed between the upper face of lever 1 and a nut 12 threaded upon stud 11 which is fixedly secured in member 4 passing freely through a suitable orifice in 95 the upper part of lever 1.

The extension 3 of lever 1 which passes between the top of valve stem 18 and roller 16 is provided on its upper face with a hardened plate 14 having a cam face 15 directed 100 toward the roller 16.

Lever 1 also carries a member 7 provided with a cam contacting roller 8, which member 7 is suitably secured to said member 1 so that the operation of cam 9 upon roller 105 8 will rock lever 1 upon eccentric 5 to operate valve 20.

In operation the rotation of shaft 6 and eccentric 5 from the position illustrated in Fig. 1 in a counter clockwise direction will 110 operate first to elevate the entire lever 1 and then to carry the entire lever forward

toward the cam 9 as illustrated in Fig. 2, thus drawing cam face 15 upon the end 3 of lever 1 under roller 16 to depress valve stem 18 and open valve 20, as illustrated. 5 This operation, it will be noted, raises roller 8 from cam 9, thus permitting the shifting of cam 9 to introduce another cam for the reverse operation of the engine, while the cylinder pressure is relieved by 10 means of manifold 22 connecting the various cylinders.

With the eccentric 5 in the position illustrated in Fig. 1 and the cam 9 in contact with roller 8, valve 20 would normally be 15 open for supplying starting air to the cylinder, but if the cylinder pressure exceeds that of the starting air supply, it is not desirable that the valve should be opened and to avoid its opening under the 20 circumstances, the valve 1 is flexed as previously described, spring 13 being compressed to substantially balance the cylinder pressure so that when the cylinder pressure equals or is in excess of starting air 25 pressure, valve lever 1 will be held in its elevated position by valve stem 18 controlled by the cylinder pressure operating upon valve head 20 and cam 9 will operate merely to flex member 4 relative to valve 30 lever 1, as illustrated in Fig. 1. Obviously if the cylinder pressure in the situation illustrated in Fig. 1 is less than the expansive force of spring 13, valve lever 1 will be forced by spring 13 to seat against 35 the upper face of member 4, thus opening valve 20.

Various modifications in the precise form and arrangement of the parts will readily suggest themselves to those skilled in the 40 art, but all within the scope of the present invention.

Having thus fully described my invention, I claim:

1. A valve opening mechanism for the 45 relief of cylinder pressure comprising in combination a valve having a reciprocating stem, a guide mounted above the top of the valve stem and spaced therefrom, an eccentrically mounted cam lever for operating 50 the valve stem having one end provided with a cam face, said cam faced end of

the lever being located between the top of the valve stem and the guide so that the operation of the eccentric mounting of said lever will draw said cam face under the 55 guide to depress the valve stem.

2. A valve opening mechanism for the relief of cylinder pressure comprising in combination a valve having a reciprocating stem, a roller mounted above the top of the valve stem and spaced therefrom, an eccentrically mounted cam lever for operating the valve stem having one end provided with a cam face, said cam faced end of the lever being located between the top of the 60 valve stem and the roller so that the operation of the eccentric mounting of said lever will draw said cam face under the roller to depress the valve stem.

3. A valve opening mechanism comprising a cam lever in two parts, one part having a slot in one side, the other part being narrower than said slot and adapted to seat therein, said last mentioned part being eccentrically mounted and adapted to 70 contact with a valve operating cam, and tension means for holding said parts in flexed relation.

4. A valve opening mechanism for the relief of cylinder pressure comprising in combination a valve having a reciprocating stem, a roller mounted above the top of the valve stem and spaced therefrom, an eccentrically mounted cam lever in two parts for operating the valve stem, one of said parts 75 having a slot in one side and a cam faced end, said cam faced end being located between the top of the valve stem and the roller so that the operation of the eccentric mounting of said lever will draw said cam 80 face under the roller to depress the valve stem, the other part of the valve lever being narrower than said slot in the first part and adapted to seat therein, said last mentioned part being provided with the eccentric 85 mounting and adapted to contact with a valve operating cam, and tension means for holding said parts of the valve lever in fixed relation.

In testimony whereof I affix my signature. 100

AXEL AUGUST ASPLUND.
